(57) **CLAIM**

The ornamental design for a music stand, as shown and described.

DESCRIPTION

FIG. 1 is a first perspective view of a music stand showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1;

FIG. 9 is an enlarged view of an encircled portion of the music stand labeled 9 in FIG. 1; and,

FIG. 10 is an enlarged view of an encircled portion of the music stand labeled 10 in FIG. 2.

The evenly-dashed broken lines shown in the drawings depict portions of the music stand that form no part of the claimed design. The dash-dot broken lines encircling portions of the music stand illustrated in enlargements form no part of the claimed design.
